DESIGN FOR A WARNING SIGNAL

Foster E. Weld, Newton, Mass., assignor to The Gamewell Company, Newton, Mass., a corporation of Massachusetts

Application November 20, 1935, Serial No. 59,663

Term of patent 14 years

To all whom it may concern:

Be it known that I, Foster E. Weld, a citizen of the United States, residing at Newton, in the county of Middlesex and Commonwealth of Massachusetts, have invented a certain new, original, and ornamental Design for a Warning Signal, of which the following is a specification, reference being had to the accompanying drawing, forming part thereof.

Figure 1 is a front perspective view of a warning signal showing my new design; and Fig. 2 is a rear perspective view thereof.

I claim:

The ornamental design for a warning signal, substantially as shown.

In witness whereof, I hereunto subscribe my name this 18th day of November, 1935.

FOSTER E. WELD.
